UNITED STATES PATENT OFFICE

BENARD E. RODIN, OF EAST CLEVELAND, OHIO

VENTILATING APPARATUS

Application filed February 5, 1930. Serial No. 425,999.

This invention relates to a ventilating apparatus adapted for use in connection with garages and especially large garages where a great deal of work is necessarily done with 5 motors running; and the principal object is to provide an improved means for disposing of exhaust gases whereby the air is kept free from injurious or poisonous materials, especially carbon monoxide.

10 A further object is to provide a mechanism of this character which shall be extremely convenient in use and avoid the necessity of having a plurality of pipes depending from various points in the garage when the same 15 are not in use.

A further object is to provide an apparatus of this character which shall be constructed in sections which may be conveniently shipped and which will be adapted 20 for installation in various types of layouts merely by assembling certain standard units in different patterns.

A further object is to provide a roof ventilator attachment to extend above the garage and which is provided with auxiliary draft producing means adapted to assist in the eduction of gases from the interior of the garage.

Other objects will appear from the following description.

Referring to the accompanying drawings, Fig. 1 is a schematic layout showing an illustrative embodiment of my invention and the manner of using the same; Fig. 2 is a sectional view showing a detail of the connecting outlets which I employ; Fig. 3 is a sectional view at right angles to the view of Fig. 2; Fig. 4 is a partial sectional view corresponding to the view of Fig. 2 and showing the gas eduction pipe in attached position, together with the attaching means which I employ; and Fig. 5 is a detail view of a portion of the attaching means.

In Fig. 1 the numeral 10 represents the roof 45 of a garage. Mounted on the roof 10 in any suitable manner and extending therethrough is a pipe 11 upon which is rotatably mounted the ventilator 12. This ventilator is of larger size than the pipe 12 and allows the upward passage of air currents outside the pipe 11 to

assist in the production of a draft through said pipe. Attached to the roof 10 by any suitable hangers 13 are pipes 14 and 15 connected with the pipe 11 and running to various parts of the garage. These pipes are 55 made in sections, as shown, and it is evident that they may be arranged near the roof in any suitable layout so as to provide outlets at all points necessary for convenience. The outlets are illustrated schematically in Fig. 1 at 16 and are of the construction shown in Figs. 2 and 3. A flexible pipe 17 is adapted for attachment to the outlet 16 and may be connected at one end to any such outlet, and at the other end to the exhaust pipe of an 60 automobile. When the pipe 17 is not needed, the same can be conveniently hung on the wall of the garage where it will not be a nuisance, as would be the case if it were permanently attached to the outlet.

Each outlet 16 is constructed in accordance with the showing of Figs. 2 and 3. The tube 18 is connected, as shown, to the pipe 15 and extends for a short distance thereto. Mounted on the inner end of said pipe by a 70 bolt 19 is a spring member 20 attached at its other end to a valve 21. Pivoted in the pipe 18 and rigidly attached to the valve 21 is a V-shaped rod 22. Mounted on a bracket 23 at the other end of the pipe 18 is a control member 24 which is adapted to swing through a slot 25 in the pipe 18. The outward swing of the member 24 is limited by means of an outwardly struck tongue 26 which engages with the wall of pipe 18 adjacent the slot 25. This construction is rendered necessary by reason of the fact that if the outlets 16 not in use were open, there would be insufficient suction through the pipe 17 to deliver the exhaust gases or the resistance would be so great that the pressure at which the gases exhaust into the atmosphere or exhausted from the muffler would be insufficient to carry the same readily through to outer atmosphere. It might even result in discharge of the same 80 downwardly through the other openings instead of securing the desired exhaustion to outside.

The tube 17 is of well known flexible construction and is adapted to be slipped over 90

70

the lower end of the outlet 16. When this tube is pushed over the outlet, the member 24 is cammed inwardly and, engaging with the member 22, causes opening of the valve 21. The friction of the pipe 17 on the wall 18 may be relied on to hold the pipe in position, or an additional holding means may be employed, consisting of the hook 30 and the rod 31 carrying the channeled bifurcated portion 32 at the end thereof and extending at right angles thereto. The hooked portion is provided with an eye 33 and a link 34 extending through such eye and connects the same with the member 31 at the bend thereof. When this construction is employed, after pushing the pipe 17 over the lower end of the outlet, the hook 30 is caught over the top of the pipe 15 and the bifurcated portion 32 pushed over the pipe 17, while the handle 31 is held at an angle thereto so that the outer portions of the bifurcated members extend downwardly. In this position the member 32 is pushed into frictional or binding contact with the pipe 17 and then the handle 31 is pulled downwardly, which results in a tightening and a suspension of the pipe 17 by means of the hook 30. The handle is employed to lift and/or guide the flexible tube into position on the outlet.

It will be evident from the foregoing that I have provided a simple and convenient device for disposing of exhaust gases, and while I have illustrated one embodiment of my invention, I wish it understood that I am limited only in accordance with the appended claims.

Having thus described my invention, what I claim is:

1. Ventilating apparatus including a pipe 40 delivering to the exterior of a building and having a plurality of outlets inside said building; a flexible pipe and means for detachably connecting the same to one of said outlets and to the exhaust pipe of an 45 automobile.

2. Ventilating apparatus including a pipe delivering to the exterior of a building and having a plurality of outlets inside said building, a flexible pipe and means for detachably 50 connecting the same to one of said outlets and to the exhaust pipe of an automobile, each said outlet including means whereby same is closed except when said flexible pipe is connected thereto.

3. An outlet for use in connection with an apparatus of the class described including a pipe, a valve in said pipe, said outlet having means including a cam whereby when a second pipe is telescoped with the said pipe 60 said valve is opened.

4. An outlet for use in connection with an apparatus of the class described including a pipe, a valve in said pipe, said outlet having means including a cam whereby when a second pipe is telescoped with said pipe said

valve is opened, and spring means for normally maintaining said valve in closed position.

5. An outlet for use in connection with an apparatus of the class described including a pipe, a valve in said pipe, said outlet having means including a cam whereby when a second pipe is telescoped with said pipe said valve is opened, there being a slot in said pipe through which said cam member works.

6. An outlet for use in connection with an apparatus of the class described including a pipe, a valve in said pipe, said outlet having means including a cam whereby when a second pipe is telescoped with said pipe said valve is opened, there being a slot in said pipe through which said cam member works, and a projection rigid with said valve and cooperating with said cam member.

7. An outlet for use in connection with an apparatus of the class described including a pipe, a valve in said pipe, said outlet having means including a cam whereby when a second pipe is telescoped with said pipe said valve is opened, said valve comprising a disk pivoted in said pipe and rigidly attached to a spring, said spring being rigidly mounted on said pipe.

8. An outlet for use in connection with an apparatus of the class described including a pipe, a valve in said pipe, said outlet having means including a cam whereby when a second pipe is telescoped with said pipe said valve is opened, and spring means for normally maintaining said valve in closed position, said valve comprising a disk pivoted in said pipe and rigidly attached to a spring, said spring being rigidly mounted on said pipe.

9. An outlet for use in connection with an apparatus of the class described including a pipe, a valve in said pipe, said outlet having means including a cam whereby when a second pipe is telescoped with said pipe said valve is opened, there being a slot in said pipe through which said cam member works, said valve comprising a disk pivoted in said pipe and rigidly attached to a spring, said spring being rigidly mounted on said pipe.

10. An outlet for use in connection with an apparatus of the class described including a pipe, a valve in said pipe, said outlet having means including a cam whereby when a second pipe is telescoped with said pipe said valve is opened, there being a slot in said pipe through which said cam member works, and a projection rigid with said valve and cooperating with said cam member, said valve comprising a disk pivoted in said pipe and rigidly attached to a spring, said spring being rigidly mounted on said pipe.

11. Ventilating apparatus including a pipe delivering to the exterior of a building and having a plurality of outlets inside said building, a flexible pipe, means for detachably con-

necting the same to one of said outlets and to the exhaust pipe of an automobile, each said outlet including means whereby the same is closed except when said flexible pipe is connected thereto, and a hook mechanism adapted to retain said flexible pipe in position.

12. Ventilating apparatus including a pipe delivering to the exterior of a building and having a plurality of outlets inside said building, a flexible pipe, means for detachably connecting the same to one of said outlets and to the exhaust pipe of an automobile, each said outlet including means whereby the same is closed except when said flexible pipe is connected thereto, and a hook mechanism adapted to retain said flexible pipe in position, said hook mechanism including a handle portion, a bifurcated portion carried by said handle and a hook connected flexibly to one of said portions.

13. Ventilating apparatus including a pipe delivering to the exterior of a building and having a plurality of outlets inside said building, a flexible pipe, means for detachably connecting the same to one of said outlets and to the exhaust pipe of an automobile, each said outlet including means whereby the same is closed except when said flexible pipe is connected thereto, and a hook mechanism adapted to retain said flexible pipe in position, said hook mechanism including a handle portion, a bifurcated portion carried by said handle and a hook connected flexibly to one of said portions, said bifurcated portion being channel shaped in cross section.

In testimony whereof, I hereunto affix my signature:

BENARD E. RODIN.
